2,905,167

TRIGGER MECHANISM FOR SPEAR OR HARPOON GUNS

Donald J. Abrams, Whittier, and Marius R. Welland, Norwalk, Calif.

Application December 17, 1956, Serial No. 628,590

10 Claims. (Cl. 124—40)

This invention relates generally to harpoon or spear guns and the like and relates more particularly to improvements in the trigger mechanism for such guns.

While the invention has particular utility in connection with guns of this character which may be termed submarine guns for shooting fish, and is shown and described embodied in such a gun, it is to be understood that its utility is not confined thereto.

Submarine or underwater harpoon guns are provided with a harpoon or spear which is propelled by means of a spring or rubber slings. When the harpoon is in position in the gun, preparatory to being discharged, it is held in position in the gun by means of a trigger mechanism, the spring or rubber slings exerting a powerful pressure on the harpoon urging same in a direction to drive it forwardly upon its release from the part of the trigger mechanism holding said harpoon in the gun. Because of the force exerted on the harpoon by the spring or rubber slings there is a great deal of friction between the harpoon and said trigger part and also pressure thereon. With previous trigger mechanisms substantial pressure must be applied to the trigger by the trigger finger and there may be a slight delay in effecting discharge of the gun sufficient to permit the intended game to get out of range or otherwise escape.

It is therefore an object of the present invention to provide a trigger mechanism adapted to securely retain the harpoon or spear in the gun and to properly release same even under extreme load conditions such as would occur when the spring is strengthened or rubber slings are added to those normally used.

Another object of the invention is to provide mechanism of this character that has a simple and effective trigger return means.

Still another object of the invention is to provide mechanism of this character which securely retains the harpoon in position in the gun but which requires a minimum of pressure or force to actuate the trigger and release the harpoon.

A further object of the invention is to provide a mechanism of this character upon which the corrosive action of salt water will be greatly reduced or substantially eliminated.

A still further object of the invention is to provide a mechanism of this character which may be easily and quickly dismantled for cleaning, inspection or repair with merely a screw driver, coin or other simple tool.

Another object of the invention is to provide a mechanism of this character wherein there is no reversal of the leverage applied on the trigger by the amount of load on the harpoon shaft.

Still another object of the invention is to provide a mechanism of this character having a simple, effective safety lock which prevents accidental firing.

2

A further object of the invention is to provide mechanism of this character that is extremely simple in construction and operation.

A still further object of the invention is to provide a mechanism of this character that is relatively inexpensive to manufacture.

The characteristics and advantages of the invention are further sufficiently referred to in connection with the following detailed description of the accompanying drawings which represent one embodiment. After considering this example, skilled persons will understand that many variations may be made without departing from the principles disclosed, and it is contemplated that any structures, arrangements or modes of operation that are properly within the scopes of the appended claims may be used.

Referring to the drawings:

Fig. 1 is a side elevation of a gun embodying the present mechanism, only a portion of the barrel and harpoon or spear being shown;

Fig. 2 is a similar view with a portion shown in longitudinal section to show the trigger mechanism;

Fig. 3 is a sectional view taken on line 3—3 of Fig. 2;

Fig. 4 is a sectional view taken on line 4—4 of Fig. 1;

Fig. 5 is a view taken from line 5—5 of Fig. 3;

Fig. 6 is a view taken from line 6—6 of Fig. 2; and

Fig. 7 is a side view of the rear end portion of the harpoon or spear shaft.

Referring more particularly to the drawings, there is shown the rear portion of a harpoon or spear gun which comprises a body portion, indicated generally at 10, from which depends a handle or pistol grip 11. A cylindrical barrel support 12 extends forwardly from the body and includes a reduced diameter portion 14 which is received in the rear end portion of a tubular barrel 15, which is secured thereon by a screw 16 which extends through diametrically arranged openings provided therefor in said rear end portion of the barrel 15 and through an opening provided therethrough in said reduced diameter portion 14.

Barrel support 12 is spaced downwardly of the plane of the upper or top side 17 of the body so that there is shoulder 18, the plane of which is substantially normal to the axis of said barrel support. A horizontal bore 19 extends from the front face of said shoulder 18 for reception of the rear end portion 20 of a spear or harpoon 21, Fig. 7, there being a collar 22 at the forward end of said harpoon or spear portion 20.

Beneath the bore 19 is a chamber 25 for reception of a trigger plate 26 separated by a horizontal partition 27. The width of said chamber in a transverse direction is slightly greater than the thickness of the plate 26. There is a bore 28 in said partition 27, extending from said bore 19 downwardly into the upper end of said chamber

25, a continuation 28a of said bore 28 extending downwardly to the bottom side or edge of the body 10. At the rear of the chamber 25 is a vertical bore 29 extending from the upper side 17 of the body to a point below the bottom edge 30 of the body 10 and communicating with said chamber by means of a slot 31 which extends downwardly from the plane of the top of the chamber 25, said slot extending to the front of the grip 11 a limited distance below said bottom edge 30 of the body.

The trigger 26 comprises a relatively flat plate of metal and includes a main body portion 33 having a transverse opening therethrough for pivotal reception of and support by a pivot pin 34 which is received in aligned openings provided therefor in the portions 35 of the body de-

fining the sides of the chamber 25. Pin 34 has a relatively flat-convex head 36 at one end and an annular groove adjacent the opposite end for reception of a generally U-shaped wire retainer 37 which secures the pin in place, said retainer being easily attached to the pin 34 and removed therefrom when it is desired to dismantle the trigger mechanism. The upper forward edge portion 40 of the trigger body 33 is arcuate in shape and has a radius centered on the axis of the pivot pin 34. Beginning at the rear end 41 of the edge portion 40 and curving 10 arcuately downwardly and rearwardly is a notch 44. At the rear of the notch 44 is a projection 45 from which an arcuate notch 46 extends downwardly and somewhat rearwardly. The trigger has a projection 48 which extends downwardly and rearwardly and is provided with a straight edge portion 49 inclined downwardly and rearwardly, the free end of said projection 48 extending through the slot 31 into said bore 29. There is also a downwardly and forwardly curved fingers engageable trigger member 50.

Means is provided for urging the trigger member 50 to the normal forward position and said means comprises a ball 52 movable in said bore 29 and urged to the lower end of said bore by a spring 53 which is held within said bore 29 by means of an annular screw 54 threadably received in the upper end of bore 29 and having a longitudinal opening 55 therethrough to prevent trapping of water above the ball 52 which would interfere with the actuation of the trigger. Slots 56 in the upper end of the screw are provided for reception of a screw driver, coin or the like to actuate said screw 54. The ball 52 is engaged by the straight edge 49 of the trigger and when the trigger member 50 is pulled rearwardly to actuate the trigger plate in a counterclockwise direction the ball is moved upwardly in the bore 29 against the force of spring 53, the latter forcing the ball to the bottom of the bore 29 when the trigger member 50 is released to move the trigger plate clockwise. When the ball is at the bottom of bore 29 the trigger is moved to the normal forward position.

The axis of the bore 28 and continuation 28a thereof is vertical and intersects the axis of the pivot pin 34 of the trigger and a ball 58 is operably received in the bore 28; being easily slidably therein. This ball normally rests on the arcuate portion 40, the rear end 41 of which is positioned rearwardly of the axis of the bore 28 when the trigger is in the normal position shown in Figs. 1 and 2. With the trigger in the normal position thus supporting ball 58 there is an upper section of the ball which extends upwardly into the bore 19 which is somewhat smaller in diameter than the diameter of the ball so that the latter cannot inadvertently escape through said bore 19.

When the trigger is in the normal position the portion 40 supports the ball as shown in Fig. 2. When the trigger is moved in the counter clockwise direction by applying rearward pressure on the member 50 the ball rides on said arcuate portion 40 until the rear end 41 of said portion 40 passes forwardly through the axis of the bore 28, whereupon the ball moves downwardly along the face of said notch 44 until the upper portion of said ball moves downwardly out of the bore 19. It will be readily apparent that because the radius of the portion 40 is centered on the axis of the pivot pin 34 for the trigger plate the ball 58 will not move vertically either upwardly or downwardly as long as it rides on said portion 40 so that the trigger will move very easily and with little effort. The spring 53 is readily compressed when the trigger member 50 is pulled but is sufficiently strong to move the trigger back to the normal position when said trigger member is released, the bottom of notch 44 moving the ball upwardly into the bore 19, as shown in Fig. 2.

In loading the gun the trigger member 50 is pulled rearwardly to clear the bore 19. The rear end portion 70

20 of the harpoon or spear is then inserted into said bore with notch 60 thereof facing downwardly, the trigger then being released permitting the ball 58 to be moved upwardly into the bore 19 and into said notch 60 which snugly receives said ball. The ball 58 cannot move downwardly as long as it rides on portion 40 because the center of said ball is on the axial line of the bore 28 and directly above the axis of the pivot 34. Pulling the trigger member 50 permits the ball to descend out of the bore 19 and release the harpoon or spear.

There is a trigger guard 62 which includes a horizontal portion 63, the free end of which is removably received in a slot provided therefor in the front of the grip 11. At the opposite end of portion 63 there is a vertical portion 64 and at the upper end of said vertical portion there is a rearwardly turned end portion 65 having an opening therein for reception of a retaining screw 66.

Means for retaining the line indicated at 67, is provided, said means comprising a hub 68 rotatably mounted 20 on the screw 66 between the trigger guard portion 65 and the under side of the barrel support 12. There are a pair of oppositely arranged short spokes 70 secured to the hub 68 and a pair of oppositely arranged long spokes 71 disposed at right angles and between the short spokes. When the trigger is in the normal position a portion thereof is in the path of the longer spokes and one of said longer spokes engages the trigger plate when the line is releasably disposed on one of the short spokes. The slings are secured to the barrel and harpoon or spear in the well known manner and when the trigger member 50 is pulled to release the harpoon or spear the trigger plate moves out of the path of said long spoke permitting the hub to rotate and release the line from the short spoke to which it is attached.

35 Safety means is provided which comprises a shaft 75 rotatably received in a transverse opening provided therefor in the body 10. At one end the shaft 75 is provided with a flange 76 from which there is a radially extending lever 77 for rotating said shaft and preventing said shaft from sliding axially to the right, as shown in Fig. 4. At the opposite end is a tapped axial bore for reception of a screw 78, the head of which prevents said shaft from sliding to the left, as viewed in said Fig. 4. The inner side of flange 76 is provided with a pair of recesses 80 spaced arcuately apart substantially 90°, one of said recesses being shown in Fig. 4.

50 A spring 81 is received in a bore provided therefor in the body beneath the flange 76 and urges a ball 82 outwardly against the flange, said ball being adapted to enter either of the recesses 80 to position and releasably retain the shaft 75 in respective rotative positions. When said shaft is in one position a notch 84 is so positioned with respect to the projection 45 of the trigger plate that the free end portion of said projection passes through said notch when the trigger is rotated. When the shaft is positioned in its locking or safety position the notch 84 is rotated 90° and the adjacent portion of the shaft 75 is in the path of the free end portion of said projection 45 so that the trigger cannot be rotated in the counter clockwise direction.

55 The body, gun support portion and grip portion may be of any suitable material, such as for example a plastic or the like and the metal parts may be of a material that is extremely resistant to the corrosive action of sea water. These parts may be of stainless steel or may be plated with corrosion resisting material.

60 It is to be noted that the device may be easily assembled or taken apart. All that is needed is a screw driver or even a coin that will fit into the tool slots of the several screws, the pivot pin 34 being released by slipping the clip 37 from the groove provided therefor in the pivot pin 34. The clip is also easily replaced and the ball 58 is placed in or removed from the bore 28 through the continuation or extension 28a thereof.

65 It is thought that the invention and many of its at-

tendant advantages will be understood from the foregoing description and it is thought that it will be apparent that various changes may be made in the form, construction and arrangement of the parts of the invention without departing from the spirit and scope thereof or sacrificing all of its material advantages, the form hereinbefore described being merely by way of example of one embodiment.

We claim:

1. A harpoon gun, including: a body of plastic material having a depending grip and a cylindrical forwardly extending barrel support, a portion of said body extending upwardly of the top of the barrel support and having a forwardly opening bore therein; a harpoon having a shaft with a rear end portion provided with an arcuate notch therein, said rear end portion being receivable in said bore; said body having a relatively narrow trigger plate chamber beneath said bore and separated therefrom by a horizontal partition having a passage therethrough, the axis of said passage being normal to the axis of said bore and extending to the bottom of said body, said passage being in communication with said chamber at the front thereof, and a second, vertical bore at the rear of said chamber and communicating throughout a substantial portion of its length with said chamber; a ball movable in the passage in said partition and axially thereof, said ball being of larger diameter than the diameter of said bore and received in said arcuate notch in said shaft; a trigger plate in said chamber having an opening for a pivot pin, said plate having a depending trigger, a rearwardly and downwardly extending arm, extending into said second bore, a projection, and an arcuate portion having a radius on the axis of said pivot pin opening, said arcuate portion being at the upper forward portion of said plate and supporting said ball in the shaft notch and terminating rearwardly of the axis of said passage, said plate having an arcuate notch beginning at the rear end of said arcuate portion and curving toward said pivot pin opening; a pivot pin received in aligned openings in the body at each side of said chamber and pivotally received in the opening in said plate, the axis of said pivot pin being directly below the passage and being intersected by the axis of said passage, said ball riding on said arcuate portion and arcuate notch of said trigger plate as the latter is pivotally actuated; a second ball in said second bore and engageable with the free end of said arm; a spring in said second bore; and a screw having an axial opening therethrough, threadably received in the upper end of said second bore, said spring reacting between said screw and the last mentioned ball to urge said trigger plate to the normal forward position, said plate being in said normal position when said ball is at the bottom of said second bore; and safety latch means, including a rotatable rod in aligned openings in the body at opposite sides of said chamber, said rod having a cut out portion; means for rotating said rod; and means for releasably retaining said rod in two positions, the projection on the trigger plate moving through said cut out portion of the rod when the latter is in one position, and when said rod is moved to the other of said positions, a portion of said rod extends into the path of said projection so that said trigger plate cannot be actuated.

2. A spear gun, including: a body having a depending grip and a cylindrical forwardly extending barrel support, a portion of said body extending upwardly of the top of the barrel support and having a forwardly opening bore therein; a spear having a shaft with a rear end portion provided with a notch, said rear end portion being receivable in said bore; said body having a trigger plate chamber beneath said bore and separated therefrom by a horizontal partition having a passage therethrough, the axis of said passage being normal to the axis of said bore and extending to the bottom of said body, said passage being in communication with said chamber at the front thereof, and a second, vertical bore at the rear of

70
75

said chamber and communicating throughout a substantial portion of its length with said chamber; a ball movable in the passage and axially of said passage, said ball being of large diameter than the diameter of said bore and received in said arcuate notch in said shaft; a trigger plate in said chamber having an opening for a pivot pin, said plate having a depending trigger, a rearwardly and downwardly extending arm, extending into said second bore, and an arcuate portion having a radius on the axis of said pivot pin opening, said arcuate portion being at the upper forward portion of said plate for supporting said ball in the first mentioned bore and notch, said arcuate portion terminating rearwardly of the axis of said passage, said plate having an arcuate notch beginning at the rear end of said arcuate portion and curving toward said pivot pin opening; a pivot pin received in aligned openings in the body at each side of said chamber and pivotally received in the opening in said plate, the axis of said pivot pin being directly below the passage and being intersected by the axis of said passage, said ball riding on said arcuate portion and arcuate notch of said trigger plate as the latter is pivotally actuated; a second ball in said second bore and engageable with the free end of said arm; a spring in said second bore; and a screw having an axial opening therethrough, threadably received in the upper end of said second bore, said spring reacting between said screw and the last mentioned ball to urge said trigger plate to the normal forward position, said plate being in said normal position when said ball is at the bottom of said second bore.

3. A spear gun, including: a body having a depending grip and a cylindrical forwardly extending barrel support, a portion of said body extending upwardly of the top of the barrel support and having a forwardly opening bore therein, said body having a relatively narrow trigger plate chamber beneath said bore and separated therefrom by a horizontal partition having a passage therethrough with an axis normal to the axis of said bore and extending to the bottom of said body, said passage being in communication with said chamber at the front thereof, and a vertical bore at the rear of said chamber, communicating with said chamber; a ball movable axially in the passage in said partition, said ball being of larger diameter than the diameter of said bore; a trigger plate in said chamber having an opening for a pivot pin, said plate having a depending trigger, a rearwardly and downwardly extending arm, a free end portion thereof extending into said vertical bore, and an arcuate portion having a radius on the axis of said pivot pin opening, said arcuate portion being at the upper forward portion of said plate and terminating rearwardly of the axis of said passage, said plate having an arcuate notch beginning at the rear end of said arcuate portion and curving toward said pivot pin opening; a pivot pin received in aligned openings in the body at each side of said chamber and pivotally received in the opening in said plate, the axis of said pivot pin being directly below the passage and being intersected by the axis of said passage, said ball riding on said arcuate portion and being held thereby with an upper portion of said ball projecting into the first mentioned bore, said ball also riding on the bottom of said arcuate notch of said trigger plate as the latter is pivotally actuated; a second ball in said vertical bore and engageable with the free end of said trigger plate arm; a spring in said vertical bore; and a screw having an axial opening therethrough, threadably received in the upper end of said second bore, said spring reacting between said screw and the last mentioned ball to urge said trigger to the normal forward position.

4. A harpoon gun, including: a body having a depending grip and a forwardly extending barrel support, a portion of said body extending upwardly of the top of the barrel support and having a horizontal, forwardly opening bore therein; a harpoon having a shaft with a rear end portion provided with an arcuate notch, said

rear end portion being receivable in said bore; said body having a trigger plate chamber beneath said bore and separated therefrom by a horizontal partition having a passage therethrough, the axis of said passage being normal to the axis of said bore and extending to the bottom of said body, said passage being in communication with said chamber at the front thereof; a ball movable in the passage and axially thereof, said ball being of larger diameter than the diameter of said bore and received in said arcuate notch in said shaft; a trigger plate in said chamber having an opening for a pivot pin, said plate having a depending trigger, and an arcuate portion having a radius on the axis of said pivot pin opening, said arcuate portion being at the upper forward portion of said plate for supporting said ball in said bore and shaft notch, said arcuate portion terminating rearwardly of the axis of said passage, said plate having an arcuate notch beginning at the rear end of said arcuate portion and curving toward said pivot pin opening; a pivot pin received in aligned openings in the body at each side of said chamber and pivotally received in the opening in said plate, the axis of said pivot pin being directly below the passage and being intersected by the axis of said passage, said ball riding on said arcuate portion and bottom of the arcuate notch of said trigger plate as the latter is pivotally actuated; and yielding means urging said trigger plate to a normal trigger position.

5. A spear gun, including: a body having a depending grip and a barrel support, said body having a forwardly opening spear shaft receiving bore therein, and a trigger plate chamber beneath said bore and separated therefrom by a horizontal partition having a passage therethrough with an axis normal to the axis of said bore; a ball movable longitudinally in the passage in said partition, said ball being of larger diameter than the diameter of said bore; a trigger plate in said chamber having an opening for a pivot pin, said plate having a depending trigger, and an arcuate portion having a radius on the axis of said pivot pin opening, said arcuate portion being at the upper forward portion of said plate and terminating rearwardly of the axis of said passage and supporting said ball with an upper portion thereof extending into said shaft receiving bore, said plate also having a ball retracting portion beginning at the rear end of said arcuate portion approaching said plate opening; a pivot pin received in aligned openings in the body at each side of said chamber and pivotally received in the opening in said plate, the axis of said pivot pin being directly below the passage and being intersected by the axis of said passage, said ball riding on said arcuate portion and said ball retracting portion of said trigger plate as the latter is pivotally actuated; and yielding means urging the trigger plate to a normal position whereat said ball is on said arcuate portion.

6. A spear gun, including: a body having a depending grip and a forwardly extending barrel support, a portion of said body extending upwardly of the top of the barrel support and having a forwardly opening bore therein for reception of a rear end portion of a spear shaft; said body having a ball receiving opening below said bore and communicating therewith; with a ball in said opening adapted to move into the bore but of somewhat larger diameter than said bore; a trigger plate pivotally mounted in said body and having a depending trigger member, the pivotal axis of said trigger plate being directly beneath the center of the ball and said trigger plate having an arcuate portion on which said ball rides, the radius of which is on the axis of the pivot of said plate, said arcuate portion normally extending forwardly and rearwardly of said ball, said plate also having an arcuate notch beginning at the rear end of the arcuate portion and curving toward the pivot; yielding means urging the trigger plate in a direction to position the trigger member in the normal forward position; and safety means having one position whereat the trigger

plate is held against movement and another position wherein the trigger plate is released for actuation.

7. A spear gun, including: a body having a hand grip and a forwardly extending barrel support, a portion of said body extending upwardly of the top of the barrel support and having a forwardly opening bore therein for reception of a rear end portion of a spear shaft; said body having a ball receiving opening extending from said bore; a ball in said opening, a substantial portion of said ball being adapted to move into the bore which is of somewhat smaller diameter than said ball; a trigger plate pivotally mounted in said body and having a depending trigger member, the pivotal axis of said trigger plate being aligned with the path of movement of the ball, said trigger plate having an arcuate portion, the radius of which is on the axis of the pivot of said plate, said portion extending forwardly and rearwardly of said path, said plate also having an arcuate notch beginning at the rear end of the arcuate portion and curving toward the pivot; yielding means urging the trigger plate in a direction to position the trigger member in the normal forward position.

8. A harpoon gun, including: a body having a grip and a barrel support, said body having a forwardly opening bore therein for reception of a spear shaft; said body having a ball receiving opening below said bore and communicating therewith; a ball in said opening adapted to move into and out of said bore; a trigger plate pivotally mounted in said body and having a trigger member, the pivotal axis of said trigger plate being aligned with the path of movement of said ball, said trigger plate having an arcuate portion, the radius of which is on the axis of the pivot of said plate and extending forwardly and rearwardly thereof, said plate also having a notch beginning at the rear end of the arcuate portion and approaching the pivot, said ball riding on said arcuate portion and into said notch as said trigger plate is actuated; and yielding means urging the trigger plate in a direction to position the trigger member in the normal forward position whereat the ball is on said arcuate portion with a portion extending into said bore.

9. In a device of the class described: a body having an opening for reception of a portion of a spear shaft; a ball operably mounted in said body for movement into and out of locking engagement with said shaft; a trigger plate pivotally mounted in said body and having a trigger member engageable by a finger of the user, said plate including an arcuate portion, the radius of said arcuate portion being on the pivotal axis of said plate, the axis of said plate being aligned with the path of movement of said ball and said arcuate portion backing the ball when the ball is in the locking position, said plate having an arcuate notch beginning at the rear end of said arcuate portion and curving toward the pivot of said plate and into which the ball rides as the trigger plate is actuated so that the ball moves out of the locking position; and means for urging the trigger plate to a normal position whereat the ball is backed by said arcuate portion.

10. In a device of the class described: a body having an opening for reception of a portion of a spear shaft; a ball operably mounted in said body and having a path of movement into and out of locking engagement with said shaft; a trigger plate pivotally mounted in said body and having a trigger member engageable by a finger of the user, said plate including an arcuate portion, the radius of said arcuate portion being on the pivotal axis of said plate, the axis of said plate being aligned with the longitudinal center of said path and said arcuate portion being arranged to back the ball when the ball is in the locking position, said plate also having an arcuate notch beginning at the rear of said arcuate portion and curving toward the pivot of said plate, said ball riding into said notch as the trigger plate is actuated and thereby moving out of locking engagement with said shaft; and means

for urging the trigger plate to a normal position whereat the ball is in engagement with said arcuate portion.
